UNITED STATES PATENT OFFICE.

CARLON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

APPARATUS FOR CRACKING HYDROCARBON OILS.

Application filed February 4, 1925. Serial No. 6,782.

To all whom it may concern:

Be it known that I, CARLON P. DUBBS, a citizen of the United States, residing at Wilmette, in the county of Cook and State of Illinois, have invented certain new and useful Improvements in an Apparatus for Cracking Hydrocarbon Oils, of which the following is a specification.

This invention relates to an apparatus of cracking hydrocarbon oils and has among its salient objects, to provide an improved apparatus in which the vapors which pass off from the vapor chambers are subjected to the action of a reflux condenser and the condensed portions thereof returned to the system at a point remote from the vapor zone; to provide an apparatus of the character above referred to in which the condensate from the reflux condensers is returned to or near a point where the oil to be treated enters the system and at a relatively cool part of the system; to provide an apparatus of the character above referred to in which the oil is subjected to the pressure of the generated vapors during treatment; to provide an apparatus adapted for continuous operation as distinct from batch operation.

The invention further provides an apparatus wherein a pump may be utilized for forcing the hot reflux at a high velocity through the heating coil, in combination with an oil conducting line by means of which the reflux oil can be returned to the coil under a head pressure in the event the pump becomes disabled, thereby permitting the plant to continuously operate while the pump is being replaced or repaired. With this conception in mind, it will be understood that a body of oil is held above the pump, and suitable controlling devices are disposed adjacent the pump and in the bypass therefor to permit the pump to be bypassed when desired at which time the reflux oil will feed to the stream under a head pressure.

This application is a continuation in part of my co-pending application Serial No. 266396, filed December 12, 1918.

In the drawings:

Figs. 1 and 1^a together form a side elevation of the apparatus with parts shown in section.

Figs. 2 and 2^a together form a plan view

with parts shown in section and other parts broken away.

Referring to the drawings, 1 designates the furnace provided with bridge wall 2, flue 3 and stack 4. The furnace may be separated into two compartments by means of dividing wall 5. Within the furnace chambers are mounted two sets of tubes 6 and 7 mounted on suitable supports 8. The tubes 6 are relatively smaller than the tubes 7. The tubes 6 may be from an inch in diameter to six inches and the tubes 7 from 8 inches to 20 inches in diameter, although it is to be understood that I do not limit myself to a tube of any particular size nor to the number or length of the tubes. These must vary as conditions require and will be apparent to one skilled in the art. The ends of the tubes are provided with cap members 9 which can be removed to permit the ends of the tubes being opened and the tubes cleaned. Instead of removing the caps 9 they may be provided with suitable doors or closure members (not shown). The oil to be treated is fed by means of a pump (not shown) from any source of supply through the feed pipe 10 to one end of the coil 6 as shown at 11. The pipe 10 may be provided with a controlling valve 12. The oil passes through the coil 6 where it reaches a cracking heat and the oil while in a substantially liquid phase is then delivered through connecting pipe 13 to one end of the large coil 7 as shown at 14. The vapors can pass out of the coil 7 through upright pipe 15 which is connected at its lower end to manifold 16 leading from adjacent ends of the large tubes of the coils 7. At its upper end, the pipe 15 is connected to a horizontal cross pipe 17 from either end of which lead downwardly extending vapor lines 18 and 19. In a generally similar manner, the other end of the large coil 7 is connected to riser 20, the upper end of which is connected to horizontal branch pipe 21 which is provided with a pair of downwardly extending vapor lines 22 and 23. The downwardly inclined vapor lines 18, 22, 23 and 19 are connected to tank 24. This tank 24 connects with an aerial condenser 25 provided with a series of upright pipes 26. The upper end of the aerial condenser is connected by pipes 27 and 28 to a water condenser 29. The water condenser 29 is connected by the pipe 30 to a

receiving tank 31. The condensed vapors are drawn off through pipe 32 controlled by throttle valve 33. The gas escape pipe 34 is also provided with throttle valve 35. The 5 receiving tank is provided with pressure gauge 36, liquid level glasses 37 and safety valve 38.

As a novel feature in the operation of apparatus, the vapors which are condensed in 10 the lines 18, 22, 23 and 19 and in the aerial are collected in the tank 24. The condensed vapors from the tank 24, which tank serves in effect as a reservoir, are drawn out from the end of the tank from pipe 39 to pipe 40.

15 From pipe 40 the condensed vapors are delivered by pipe 41 to the small coil 6 as shown at 42. These condensed vapors can either pass by gravity to the coil or can be forced in by means of a pump 43. This 20 pump is interposed in the line 40 by branches 44 and 45 controlled by valves 46 and 47. A valve 48 is interposed in the line 40. When the valves 46 and 47 are closed, the pump is not used in which case the valve 25 48 is open. If it is desired to use the pump, the valve 48 is closed and the valves 46 and 47 opened. The oil is drawn off from the 30 larger coil through the draw-off lines 52 and 53 controlled by the valve 54. Gas or fuel oil for the burners are fed through lines 49 to pipes 50 and 51 which supply the burners. It will be understood that the hot reflux oil when the valve 48 is closed and the valves 46 and 47 open, passes into the pump where 35 it is forced under high velocity through the line 41 to the heating coil. Should this pump become disabled because of the terrific heat it is subjected to or for any other reason, the valves 46 and 47 may be closed 40 and the valve 48 opened, at which time the reflux oil will continuously feed from the enlarged receiver 24 through the line 41 to the heating coil under a head pressure permitting the apparatus to continuously operate by reason of the fact that the pump has 45 been by-passed.

The apparatus is operated as follows: The oil is fed into the small coil continuously at desired rate and is there subjected 50 to heat. The oil as it passes through the smaller coil may be said in effect to pass through the heating zone where it receives its cracking heat. The oil then passes to the larger coil constituting a reacting, cracking 55 or vapor zone. The undistilled portion of the oil is drawn off through the draw-off lines to a residuum tank. The vapors pass through the downwardly inclined vapor lines to the tank 24. The heavier vapors 60 will condense either in the downwardly inclined lines in the tank or in the aerial and will be drawn from the tank by gravity or by means of the pump back to the inlet side of the small coil. The advantage of this 65 method of treating the heavy condensed vapors is that they are continuously being returned to the heating zone, but inasmuch as they are not permitted to fall back into the vapor zone as is the usual process, they do not tend to unduly cool the vapors in the 70 vapor zone. This method of handling the heavy condensed vapors not only greatly lowers the fuel cost but results in a better operation. By controlling the temperature of the tank 24 and the vapor lines, anything 75 above the given boiling or end point can be prevented from passing to the water condenser. This can be controlled either by the amount of area of the vapor lines or by applying a cooling medium (not shown) to 80 the tank 24. In operating the apparatus, the oil passes first through the heating coil 6 where it attains a temperature of, say, 800° F. at the time it reaches the line 13. This oil is then delivered to the reacting or 85 vapor tubes 7 where no additional heat need be applied, provided said tubes are insulated against heat losses. If the tubes are not insulated, some heat may be applied sufficient to keep the oil at near about its former temperature, this additional heat manifestly merely offsetting the heat losses due to vaporization. A single enlarged insulated chamber can be used in lieu of the 90 tubes 7, and this chamber may or may not be heated. The pressure maintained throughout the apparatus is preferably in 95 excess of 50 pounds per square inch and may range up to a pressure in excess of 300 100 pounds per square inch. The oil is forced so rapidly through the coil 6 that no substantial amount of carbon adheres to the walls of the coil. In fact, the rapidity of the travel of the oil is such that that degree of conversion does not occur in the coil as to cause the production of such a great amount of carbon that would saturate the oil and cause adherence of carbon to the 105 walls of the tubes. The major part of the reaction occurs in the enlarged chamber 110 where no heat is applied.

The following illustrative run may be given; in cracking gas oil from the Kansas or Oklahoma fields of from 32° to 34° 115 Bauné gravity at the same time maintaining a pressure of from 100 to 150 lbs. upon the system, a yield of from 50% to 60% distillate may be obtained. By redistillation about 50% distillate may be obtained therefrom, having a boiling point of approximately 400° F.

Having thus described the invention, what I claim is:

1. In an apparatus for converting oil, the combination with an elongated heating coil, of a furnace within which said coil is disposed, an enlarged reaction zone, means for passing heated oil from said heating coil to said reaction zone, a dephlegmator disposed 125 away from said heating coil, means for pass-

- ing generated vapors to said dephlegmator, means for withdrawing unvaporized oil from said reaction zone without permitting entrance thereto to the heating coil, a conduit 5 leading from said dephlegmator, a pump communicating with said conduit, a communication between said pump and said heating coil for introducing reflux oil to the coil under pressure, and means for admitting reflux oil from said dephlegmator continuously to the inlet of said heating coil in the event said pump is shunted.
2. In an apparatus for converting oil, the combination with an elongated heating coil, 15 of a furnace within which said coil is disposed, an enlarged reaction zone, means for passing heated oil from said heating coil to said reaction zone, a dephlegmator disposed away from said heating coil, means for passing generated vapors to said dephlegmator, means for withdrawing unvaporized oil from said reaction zone without permitting entrance thereto to the heating coil, a conduit 20 leading from said dephlegmator, a pump communicating with said conduit, a communication between said pump and said heating coil for introducing reflux oil to the coil under pressure, means for admitting reflux oil from said dephlegmator under a 25 head pressure continuously to the inlet of said heating coil in the event said pump is shunted, means for introducing charging stock to the heating coil, and means for maintaining a superatmospheric pressure on 30 the oil undergoing conversion in said apparatus.
3. In an apparatus for cracking hydrocarbon oil, the combination with a heating tube through which a stream of oil is passed, 35 a furnace in which said tube is heated, an enlarged reaction zone communicating with the heating tube for receiving heated hydrocarbon materials therefrom, a reflux condenser, means for passing vapors from said 40 enlarged reaction zone to the reflux condenser, means for collecting reflux condensate from said condenser in a body, a reflux pump for forcing said reflux condensate to the inlet of the heating tube under pressure, 45 means for by-passing said pump to admit reflux condensate under a head pressure to said heating tube when said pump is inactive, and means for maintaining a superatmospheric pressure on the oil undergoing 50 conversion.
4. In an apparatus for cracking oil, the combination with a heating coil, of a furnace in which said coil is disposed, an enlarged oil reacting zone receiving oil heated 55 in said coil, dephlegmating means, a communication 60 between said reacting zone and said dephlegmating means, means for preventing the return of unvaporized oil from said reacting zone to said coil, a communication between the dephlegmating 65 means and said coil, a mechanical pressure applying element in said communication for forcing reflux oil to the inlet of the coil under pressure, means for conveying reflux oil from the dephlegmating means around 70 said pressure applying element when said element is not operating, and means for maintaining a superatmospheric pressure on the oil undergoing conversion.
5. In an apparatus for converting oil, the combination with a heating coil, a furnace in which said coil is disposed, an enlarged reaction chamber in communication with the heating coil, dephlegmating means, means for passing generated vapors from said reaction chamber to said dephlegmating means, means for withdrawing unvaporized oil from the reaction chamber without again admitting the same to the heating coil, a reflux pump in communication with the dephlegmating means for forcing reflux condensate to the heating coil under pressure, means for conveying the reflux condensate from the dephlegmating means around said pump to the inlet of the heating coil, means for selectively controlling the passage of the reflux oil to said pump or said last mentioned reflux conveying means, and means for maintaining a superatmospheric pressure on the oil undergoing conversion.
6. In an apparatus for converting oil, the combination with a heating coil, of a furnace in which said coil is disposed, an enlarged reaction chamber, means for passing heated oil from said heating coil to said reaction chamber, dephlegmating means in communication with said reaction chamber, means for discharging unvaporized oil from said reaction chamber without again admitting the same to the heating coil, a communication between said dephlegmating means and the inlet of the heating coil, a pump in said communication for forcing the stream of reflux oil to the inlet of the heating coil under an applied pressure, means establishing communication between the dephlegmating means and the inlet of the heating coil for introducing reflux oil thereto around said pump when said pump is inoperative, and means for maintaining a superatmospheric pressure on the oil undergoing conversion.

In testimony whereof I affix my signature.
CARBON P. DUBBS.
